INDIVIDUAL HUMAN WASTE DISPOSAL UNIT

William H. Wood, Chicago, Ill., assignor to Ken-Lab.
Inc., Walworth, Wis., a corporation of Delaware

Filed June 30, 1960, Ser. No. 61,171

Term of patent 14 years

(Cl. D4—5)

FIGURE 1 is a front perspective view of an individual human waste disposal unit embodying my new design; FIGURE 2 is a view similar to FIGURE 1 with the unit opened for use;

FIGURE 3 is a right side elevational view; and

FIGURE 4 is a front elevational view.

The rear is substantially plain and unornamented as indicated in FIG. 3.

I claim:

The ornamental design for an individual human waste disposal unit, substantially as shown and described.
